Attorney, Agent, or Firm—Sidney G. Faber

[57] CLAIM

The ornamental design for a solid state relay, as shown as described.

DESCRIPTION

FIG. 1 is a perspective view of a solid state relay showing my new design.

FIG. 2 is a top plan view of the solid state relay of FIG. 1.

FIG. 3 is a front elevation view of FIG. 2.

FIG. 4 is a side elevation view of FIG. 2 as seen from the left-hand side thereof.

FIG. 5 is a side elevation view of FIG. 2 as seen from the right-hand side thereof.

FIG. 6 is a bottom plan view of the solid state relay of FIGS. 1 and 2.

FIG. 1.FIG. 2.FIG. 4.FIG. 3.FIG. 5.FIG. 6.
